UNITED STATES PATENT OFFICE.

JULIAN E. CAREY, OF PLAINFIELD, NEW JERSEY, ASSIGNOR TO S. S. FISHER,
OF NEW YORK, N. Y.

DESIGN FOR ORNAMENTING CLOTH.

SPECIFICATION forming part of Design No. 12,352, dated July 12, 1881.

Application filed May 13, 1881. Term of patent 7 years.

To all whom it may concern:

Be it known that I, JULIAN E. CAREY, of Plainfield, in the county of Union and State of New Jersey, have invented a new and original 5 Design for the Ornamentation of Cloth, of which the following is a specification.

The accompanying drawing represents a face view of my design.

The design consists of a series of parallel-
10 waved lines and of short lines parallel to each other, but diagonal in direction to the waved lines, and arranged in double rows. The general effect is of alternate parallel stripes consisting of the waved lines, and of the short
15 broken diagonal lines, as shown in the accompanying drawing.

In the drawing, A represents a piece of cloth
ornamented with my new design.

B is a stripe consisting of a series of parallel-

waved lines or furrows, *b b*, which are sunk 20 into or cut from the face of the cloth.

C is a stripe parallel to the stripe B, consisting of short lines or furrows *c c*, diagonal in direction to the waved lines or furrows *b b*, but parallel with each other and arranged in double 25 rows, substantially as shown in the accompanying drawing.

I claim—

The design for ornamenting cloth, consisting of the parallel stripes B and C, the stripe 30 B being composed of waved lines *b b*, and the stripe C of diagonal lines *c c*, arranged in rows, substantially as shown.

JULIAN E. CAREY.
